UNITED STATES PATENT OFFICE

146,581

DESIGN FOR A DISPLAY CABINET

William L. Nehrenz, New York, N. Y., assignor to David Traum Company, Incorporated, New York, N. Y., a corporation of New York

Application January 21, 1946, Serial No. 125,814

Term of patent 7 years

(Cl. D80—9)

To all whom it may concern:

Be it known that I, William L. Nehrenz, a citizen of the United States and a resident of the city of New York, in the county of New York and State of New York, has invented a new, original, and ornamental Design for Display Cabinet, of which the following is a specification, reference being had to the accompanying drawings, forming part thereof.

In the drawings:

The figure is a perspective view of a display cabinet, showing my new design.

I claim:

The ornamental design for a display cabinet, substantially as shown.

WILLIAM L. NEHRENZ.
